GUY-LINE CLAMP

John M. Chevalier, Seattle, Wash.

Application April 28, 1930. Serial No. 447,879

14 Claims. (Cl. 24—125)

This invention relates to clamping devices for guy-lines, the object of which, generally, is the provision of an improved method and apparatus for attaining a most reliable and effective cable grip.

More specifically, an object of the invention is the provision of apparatus utilizing a conventional stump wrap with the elimination of heretofore costly equipment or stock loss.

10 Another object is the provision of means for effecting a most rapid handling of the work, with novel accommodations to the end of eliminating undue labor of a "rigging" crew in securing and releasing the lines.

15 A further object of the invention is the provision of novel means for effecting an embedding of the clamp body to the cable support, customarily a stump, and wherein such is effected by and responsive to tension imparted to the cable.

20 A still further object of the invention is the provision of means for safeguarding possibility of clamp release through the cooperative activity of the cable with respect to the clamp.

With the above and further objects and advantages in view, the nature of which will become apparent in the following description and claims, the invention consists in the novel construction, adaptation and combination of parts hereinafter described and set forth in the claims thereto annexed.

In the drawing,—

Figure 1 is a side elevation indicating a clamp embodying the present invention applied with respect to the guy-line and stump of a post-rigging operation. Fig. 2 is a top plan of the invention, taken to an enlarged scale, the cap member of one clamp being indicated in disengaged disposition. Fig. 3 is a side elevation with parts broken away and shown in longitudinal vertical section substantially on line 3—3 of Fig. 2, the cap members being disposed in operative positions. Fig. 4 is a transverse section indicating the application of dogs and spur to a stump.

With reference thereto, the numeral 5 represents a cable constituting the guy-line for a post (not shown) and to which the invention is adapted to be applied cooperatively with an anchor member such as a stump 6.

Heretofore, in conventional "rigging", a guy-line is given a half wrap about a stump, the eye extremity hooked to a "power cable" from the drum of a donkey engine, and pulled taut, the crew staggering spikes to the cable in retaining the same rigid with the stump, subsequent to which the "power cable" is slackened, the guy

line released, given a double wrap, again drawn taut, and spiked.

Numerous expedients have been devised to the end of overcoming the labor and consequent spike loss of a method originated in the pioneer years 60 of logging. The necessity, however, for completely changing conventional logging practice has practically eliminated extensive use of such contended improvements.

My invention is primarily conceived to the 65 end of utilizing a method of securing a guy line requiring no change in the advantageous practice of utilizing a multiple cable wrap, found most effective from protracted and extensive use.

Attention being had more particularly to Figs. 70 2 and 3, 7 represents a frame, the conformation of which provides an interconnecting web 8 between end block-supporting members 9, 10. Opposite edges of said web provide forks 11, 12 for the pivotal interposition of dogs 13, 14, the latter providing a spiked tip 15 and a driving heel member 16.

With reference to said support members, 17 represents an annular flange disposed circumferentially about block seating recessions 18, 80 85 blocks 19 being pivotally secured therein as by integrally supported studs 20 passing through axially disposed openings of the base. Exposed ends of said studs are suitably wedged to retain the same.

Diametrically opposite of the exposed block face, upstanding lugs 22 are arranged to enclose channels 23 fluted in conformity to the strand contour of a cable, said channel being cooperative with the fluting 24 of a saddle or cap member 25 for the interposition therebetween of the cable.

More particularly, said cap piece provides, laterally of the fluted channel, pin or stud projections 26 arranged in pivotal securement within a vertical recess 27 of the block member, the opposite edge presenting forks 28 for engagement over the block-retained bolt 29, clamping nut 30 securing the assembly.

With reference to Fig. 3, in assembling said bolt to the block, the latter is pivotally actuated to position a recessed aperture 32 of the substantial conformation of the bolt head in alignment to an orifice 31 of the body, providing ready insertion or removal of the bolt from the block, rigid securement to which is attained by pivotally actuating the block into bolt retained disposition, as illustrated in the several views.

33 represents a spur rigid and projecting from the underneath face 34 of the body, said spur

preferably being disposed medially of the body and in offset longitudinal disposition from the dogs.

The construction will, it is believed, be readily apparent from the foregoing. In operation, the clamp being disposed as indicated in Fig. 1, the rigger drives dog 13 to the stump in a manner to retain the clamp in operative disposition. Cable line, L is passed about the stump and through the lower block, drawn taut, and clamped.

As is believed apparent, tension imparted by the power drum embeds spur 33 to the stump, forward dog 14 being driven prior to slackening 15 the power in retaining the line in secure disposition.

The free end of the cable is passed about the stump, over the dogs and through the upper block, in double wrappings L¹ and L²; being again 20 tightened and clamped.

In releasing, turns L¹ and L² are disengaged, reversed over the stump in the direction of the live guy-line, allowing dislodgment of dog 14 from the stump, as by a bar, to effect a release 25 of the entire clamp, such being carried with the cable. The clamp is readily released from the dead line.

While I have illustrated and herein described my invention in a form now best seen to attain 30 the objectives, I do not wish to be taken as confining myself specifically thereto except as by the scope of the hereto annexed claims.

What I claim, is,—

1. The combination with a guy-line and a support therefor, of clamping devices for securing the guy-line to the support, said clamping devices comprising a frame, a pair of spaced apart annular recesses in said frame, blocks secured in said recesses, the exposed face of said blocks being channeled, saddle members having fluted channels arranged for clamping engagement over a guy-line disposed in the channels of said block, means constituting dogs adapted for engagement in said support, and means constituting a spur rigid with the frame and adapted to be embedded in the support responsive to tension imparted to the guy line passing through said blocks.

2. In cable clamping devices, the combination with a cable and a support therefor, of a clamp, said clamp comprising a frame, a pair of spaced-apart annular recesses in said frame, blocks pivotally secured for rotatory movement in said recesses, channels for said blocks, channeled cap pieces pivotally secured to said blocks for clamping engagement over a cable disposed in said block channels, flutings for said channels, and means for securing said frame to the support, said means constituting manually driven dogs and a spur, said spur being effected operative to said support responsive to pressure of the cable directly of said support.

3. In a guy-line clamp, a frame, said frame having an integral spur in the underneath side thereof adapted to be embedded in a support, a pair of blocks rotatably mounted to the exposed face of said frame, bolts carried by said blocks disposed in offset disposition from the axes, clamping nuts for said bolts, apertures arranged in said blocks at diametrically opposite sides from the bolts, saddle elements pivotally mounted in said apertures, said saddle elements providing forked free ends for straddling engagement to said bolts, grooves disposed oppositely in said pairs of blocks and saddles for the engagement of respective wraps of a guy-

line, and means cooperative with said spur for retaining said clamp in secure disposition subsequent to an initial clamping of the guy line in one of said blocks and prior to clamping such in the other of said blocks.

4. In apparatus as described in claim 3, where- 80 in said channels are fluted in substantial con- formity to the contour of the guy-line cable.

5. In a cable clamp, a frame, means carried by said frame in the underneath face adapted for embedding engagement to a support, grooved blocks rotatably supported by said frame in the exposed face for respectively receiving wraps of a cable passed about said support, saddle means carried by and adapted to seat over said blocks, and means to clamp said saddle pieces with respect to the cable in said blocks.

6. In a cable clamp, a frame, means carried by said frame in the underneath face adapted for embedding engagement to a support, grooved blocks supported by said frame in the exposed face for respectively receiving wraps of a cable passed about said support, saddle means carried by and adapted to seat over said blocks, and means to clamp said saddle pieces with respect to the cable in said blocks.

7. In a cable clamp having an integral spur arranged for embedding engagement with respect to a support, means constituting grooves in said clamp for receiving multiple wraps of a cable passed about said support, and pivotally supported means for clamping the cable selectively with respect to said grooves.

8. In a cable clamp having an integral spur arranged for embedding engagement with respect to a support, means constituting grooved blocks arranged in the exposed face of said clamp for receiving multiple wraps of a cable passed about said support, grooved saddle elements for said blocks, and means for clamping the cable 110 between.

9. In a cable clamp adapted for securement to a support, means constituting grooved blocks mounted for rotatory movement in the exposed face of said clamp for receiving multiple wraps of a cable passed about said support, grooved saddle elements for said blocks, and means for clamping the cable between respective blocks and saddle elements.

10. In a cable clamp adapted for securement to a support, laterally spaced-apart grooved blocks supported by said clamp for receiving successive turns of a cable passed about said support, grooved saddle elements for said blocks, and means for clamping the successive cable turns selectively between the respective blocks and saddle elements.

11. In a cable clamp adapted for securement to a support, means constituting grooved cable-securing blocks mounted for rotatory movement in the exposed face of said clamp, grooved saddle elements for said blocks, and means for clamping a cable between respective blocks and saddle elements.

12. In a cable clamp, a grooved cable-receiving block, a saddle therefor, means to clamp a cable between said block and the saddle, and means comprising dogs pivotally supported by said clamp and arranged for embedding engagement in a support for securing said clamp to the support.

13. In apparatus for securing a guy-line cable with respect to a supporting stump therefor, a cable-receiving clamp adapted to be positioned on a side of the stump, a dog pivoted to the

clamp and adapted for embedding engagement in the stump for initially supporting the clamp on the stump, means provided by said clamp for securely connecting the clamp with the stump responsive to a tightening of said cable around the stump, and means for securing said cable in the clamp.

14. In a clamp, a body member, a pair of laterally spaced-apart grooved blocks rotatably supported by said body member for movement about parallel axes, saddle elements for said blocks, and means to clamp the work between said blocks and saddle elements.
